UNITED STATES PATENT OFFICE.

WILLIAM W. LOWREY, OF STATEN ISLAND, NEW YORK.

DESIGN FOR A BOTTLE.

SPECIFICATION forming part of Design No. 24,580, dated August 20, 1895.

Application filed July 9, 1895. Serial No. 555,443. Term of patent 3½ years.

To all whom it may concern:

Be it known that I, WILLIAM W. LOWREY, a citizen of the United States, and a resident of Staten Island, Richmond county, in the State 5 of New York, have invented a new and useful Design for a Glass Bottle, of which the following is a specification.

In the drawings, Figure 1 represents a front elevation showing my design. Fig. 2 represents a side elevation of the same.

The leading feature of my design consists of the four flat curved surfaces forming the exterior of the body of the bottle, all four sides slightly converging toward the top of 15 the structure, while the lower edges slightly spread outwardly. Thus a sharp corner is formed at the line where the aforesaid flat sides join each other. The top of the body of the bottle is mounted with a tablet, from 20 which arises the neck of the bottle, as shown. It will be obvious that the side curved planes are formed by a long sweeping curve beginning at the top of the body of the bottle and continuing until it reaches a point just above

the base, where it makes an acute curve inwardly. 25

Similar letters refer to similar parts throughout the drawings, in which—

A represents the front and broad curved planes of the body of the bottle. 30

B represents the sides, but narrow curved planes, whose long and sweeping curve terminates at the point indicated by the letter X, from which point it continues to the base-line by an acute curve C. The top of the bottle is 35 mounted with the tablet D, from which arises the neck of the bottle.

What I claim is—

The design for a glass bottle substantially as herein shown and described. 40

In testimony that I claim the foregoing as my invention I have signed my name, in presence of two witnesses, this 10th day of June, 1895.

WILLIAM W. LOWREY.

Witnesses:

JOHN YSASI,
D. S. DOLBEAR.
